BATTERY CHARGER CASING

Lewis A. Medlar, Oreland, and Clyde Shuler,
Media, Pa., assignors to Fox Products Company,
Philadelphia, Pa., a corporation of Pennsylvania

Application April 23, 1953, Serial No. 24,635

Term of patent 14 years

(Cl. D26—5)

To all whom it may concern:

Be it known that we, Lewis A. Medlar and Clyde Shuler, citizens of the United States, and residents of Oreland, in the county of Montgomery, State of Pennsylvania, and Media, in the county of Delaware, State of Pennsylvania, respectively, have invented a new, original, and ornamental Design for a Battery Charger Casing, of which the following is a specification, reference being had to the accompanying drawings forming a part thereof.

Fig. 1 is a perspective view of a battery charger casing with the front thereof closed, showing the front, top and one side of our new design;

Fig. 2 is a top plan view of the same with the front in closed position;

Fig. 3 is a side elevation thereof with the front in closed position;

Fig. 4 is a perspective view thereof, somewhat reduced in scale, similar to Fig. 1, but with the front in open position;

Fig. 5 is a fragmentary sectional view taken on the line 5—5, Fig. 1, and

Fig. 6 is a fragmentary sectional view taken on the line 6—6, Fig. 1.

The characteristic features of our design reside in the portions shown in full lines in the drawings.

We claim:

The ornamental design for a battery charger casing, substantially as shown and described.

LEWIS A. MEDLAR.
CLYDE SHULER.
